UNITED STATES PATENT OFFICE.

WILBER R. KIRKENDALL AND GEORGE C. WOOD, OF SALINA, KANSAS.

ATTACHMENT FOR FOLDING MUSIC-STANDS.

1,359,811.

Specification of Letters Patent. Patented Nov. 23, 1920.

Application filed August 4, 1919. Serial No. 315,196.

To all whom it may concern:

Be it known that we, WILBER R. KIRKENDALL and GEORGE C. WOOD, citizens of the United States, residing at Salina, in the county of Saline and State of Kansas, have invented certain new and useful Improvements in Attachments for Folding Music-Stands; and we do declare the following to be a full, clear, and exact description of the invention, such as will enable others skilled in the art to which it appertains to make and use the same.

This invention relates to attachments for folding music stands.

One object of the invention is to provide an attachment for folding music stands having a music sheet supporting ledge made up of a pair of swinging sections, said attachment being designed to clamp the sections and form a bridge across their jointed ends to prevent them from coming out of longitudinal alinement when the frame is in open position.

Another object of the invention is to provide a device for detachable connection to the sheet supporting ledge of a collapsible music sheet supporting frame to prevent the sheets of music from sliding transversely off of the ledge.

A further object of the invention is to provide an attachment of this character which will be extremely simple, strong, durable and inexpensive in construction, and well adapted to the purpose for which it is designed.

With these and other objects in view, the invention consists of certain novel features of construction and the combination and arrangement of parts as will be hereinafter fully described and claimed.

In the accompanying drawings, forming a part of this application and in which similar reference characters designate like parts throughout the several views,

Figure 1 is a perspective view of a collapsible music sheet supporting frame, showing a device constructed in accordance with this invention applied thereto.

Fig. 2 is a transverse sectional view through the lower part of the supporting frame and the attachment, and

Fig. 3 is a perspective view of the attachment.

Referring more particularly to the drawings, a collapsible music sheet supporting frame is shown. This frame is provided

with a ledge upon which the music sheets are adapted to rest. The ledge is disposed at the lower edge of the frame and consists of a pair of sections 1 and 2 which are jointed directly or indirectly together at their inner ends so that they may swing upwardly or downwardly when the frame is folded. When the frame is in opened position the sections 1 and 2 are disposed in longitudinal alinement, but after the frame has been used for a considerable length of time the parts become worn and the joints become loose so that these sections have a tendency to slant downwardly from their jointed ends. To overcome this the present invention was devised and it consists of a rail having means for detachable connection to the sections 1 and 2 and is to be placed so as to bridge the jointed ends of the sections. This rail 3 is made from a plate bent upon itself on a longitudinal line disposed substantially midway of the edges of the frame to form an upper clamping member 4 and a lower clamping member 5. The free edges of the clamping members 4 and 5 are bent inwardly upon themselves as at 6 and 7 respectively to form parallel opposing jaw faces and to form a considerable space between the other portion of the members. The opposing jaw faces are substantially the same area as that of the opposing surfaces of the ledge above referred to. The connected ends of the members 4 and 5 are bent upwardly to form an upstanding flange 8. The flange 8 having its sides disposed at right angles to the faces of the members 4 and 5 stiffens the rail 3 and prevents it from being bent longitudinally. As the plate from which the rail is formed is resilient the members 4 and 5 are spread when anything is inserted between them. Hence they will exert a clamping action when they are snapped on the sheet supporting ledge of the supporting frame.

The device is easily applied to the supporting frame by first disposing the longitudinally alined sections 1 and 2 at the free edges of the members 4 and 5 and then by pressing the rail so as to spring the members and permit the sections to be disposed between them. When in this position, the sections 1 and 2 will be maintained at all times in longitudinal alinement. Sheets of music which may be placed upon the rail 3 will not slide transversely off of the same, this being prevented by the flange 8.

From the foregoing description, taken in connection with the accompanying drawings, the construction and use of the invention will be readily understood.

5 Various changes in form, proportion and in the minor details of construction may be resorted to without departing from the spirit of the invention as defined in the claims.

10 What is claimed is:

1. In a collapsible music sheet supporting frame, the combination of a sheet supporting ledge composed of a pair of pivotally connected swinging sections positioned in 15 longitudinal alignment when the frame is opened, and a straight rigid supplemental sheet supporting ledge having upper and lower clamping flanges receiving said sections therebetween substantially through-

out the entire length of said sections and extending across their connected ends, whereby to maintain said sections in longitudinal alignment.

2. A device of the class described comprising a plate bent upon itself intermediate 25 of its edges on a longitudinally extending line to form comparatively long straight opposing clamping members engageable with the sheet supporting ledge of a collapsible music sheet supporting frame, throughout substantially the length thereof, and the connected edges of said members being bent laterally to form a longitudinally extending sheet retaining flange.

In testimony whereof we have hereunto 35 set our hands.

WILBER R. KIRKENDALL.
GEORGE C. WOOD.
